GAMEBOARD

Douglas C. Keller, P.O. Box 94, Belford, N.J. 07718

Filed Sept. 18, 1972, Ser. No. 290,109

Term of patent 14 years

Int. Cl. D21—01

U.S. Cl. D34—5 SS

The figure is a top plan view of the playing surface of the gameboard, showing my new design.

The board is flat and of conventional thickness.

I claim:

The ornamental design for a gameboard, substantially as shown and described.
